SUPPORT FOR FLOOR SCREEDS

Edwin C. Gilson, Lexington, Ky.

Application January 5, 1938, Serial No. 183,541

5 Claims. (Cl. 72—122)

The following specification relates to an invention in supports for screeds used in the laying of concrete floors or the like.

In laying concrete floors it is the usual practice to pour the concrete over appropriate forms and around the reinforcing members such as joists and the like. Some means has been found necessary to indicate the desired depth of the concrete or the thickness of the slab generally measured from the position of the steel joist or the like. This guiding means may take the form of posts set upon the form or joist and carrying at their tops a series of screeds. In this manner the position of the screed is predetermined and will thus permit leveling the top surface of the concrete as poured and at the desired height.

Such construction offers the problem of satisfactorily gauging the height of the screed and at the same time providing for ready and convenient removal of its support after the concrete has begun to harden.

My invention provides a simple device by which the screed will be supported at any adjustable height and held in fixed position during the casting operation.

Another object of my invention is to provide means for attaching the support to the joist without risk of dislodgment or accidental change in adjustment. A further object of my invention is to provide means by which the support may be easily withdrawn from the concrete slab from beneath and leaving only a very small hole to be filled if not already filled by the settling concrete. The device constituting my invention is simple in construction, cheap to manufacture, extremely durable, and may be installed and used without requiring skill on the part of the workmen.

As showing the preferred form in which my invention may be embodied I have illustrated it in the accompanying drawing in which

Fig. 1 is a perspective view of the improved support as used on a floor joist;

Fig. 2 is a front elevation of the device, and

Fig. 3 is a vertical section taken on the line 3—3 of Fig. 1.

The support is adapted to be applied to the customary metal floor joist 4 shown in the drawing to have an upper chord 5 and a lower chord 6. Suitable truss bars 7 connect these chords.

A metal lath for casting concrete is indicated generally by the numeral 8.

The usual practice in casting the floor slab on the lath 8 is to provide a screed shown in this instance in the form of an iron pipe 9. This

pipe or screed is of course intended to be held above the joist 4 at a predetermined height and is used in leveling off the top surface of the concrete as poured.

My invention relates primarily to the support for the screed 9 and takes the following form. A member 10 shown to be in the form of a flat plate is provided of iron, other metal, wood, composition or any suitable like material. The member 10 has at one end 11, a stirrup or notch 12 of suitable proportions to hold the screed 9 against accidental displacement. It is of course desirable that the screed extend beyond the projecting end 11.

At the lower end 13 of the member there is a slot 14 which extends longitudinally of the member 10 for a considerable distance. This provides for a vertical adjustment of the supporting member 10 with respect to the associated structure with which it is used.

I also provide a clamp 15. This clamp is in the form of an iron bar of suitable size. One end of the bar is bent to form a square hook 16. This hooked end 16 is sufficiently offset from the main portion of the bar 15 to permit its engagement around the lower chord 6 of the joist while the main portion of the bar 15 passes above the chord as shown in Fig. 3.

The opposite end 17 of the bar 15 is screw-threaded and carries a nut 18. While this nut may be of the usual hexagonal or square form, I have shown it to be formed with an integral lever 19 by which the nut may be adjusted along the screw-threaded end 17.

The assembly and use of the device will be readily apparent. Where it is desired to apply this support to the joist 4 and lath 8, the latter is provided with an opening through which the upper part of the supporting member 10 will project or the form may be built around the member 10 after it has been applied.

In either event the supporting member 10 is held against the side edges of the chords 5 and 6, care being taken that the supporting member extends upwardly to the desired height. The clamping bar 15 is inserted through the slot 14 of the supporting member 10 and the hooked end 16 applied around the lower chord 6. The nut 18 will then serve to draw the clamp tightly against the joist and bring the supporting member 10 in close engagement with the opposite side of the joist.

The concrete will be poured to a height indicated by the screed 9 and before the concrete

has begun to set the clamp 15 is loosened from the supporting member 10. The member 10 may then be jarred loose from the concrete slab and drawn through the latter. In the event that this requires the application of considerable force, it may be supplied by a lever or grapple engaging the lower end 3.

The opening left by the removal of the upper end of the member 10 if not already closed by the settling concrete, may then readily be filled with concrete and the supporting device is ready for further use.

While I have shown and described the preferred form of my invention, numerous changes in proportions and minor details are of course to be considered as within the scope of the invention as defined in the following claims.

What I claim is:

- 20 1. A support for a floor screed comprising a clamp for attachment to a floor joist below its upper edge and a member for supporting a screed from beneath, said member being slotted longitudinally for adjustable connection with the clamp upwardly across and beyond the joist.
- 25 2. A support for a floor screed comprising a clamp for attachment to a floor joist below its upper edge and a flat member having a notch at one end for supporting a screed and a slot extending longitudinally of the member for receiv-

ing the clamp and adjusting the member vertically with respect to said joist.

3. A support for a floor screed comprising a clamp for attachment to a floor joist below its upper edge, said clamp having a screw threaded end, a flat member for supporting a screed from beneath, said member being longitudinally slotted to receive the said end of the clamp and to hold the member in vertically adjusted position relatively to said joist, and means on said clamp end to maintain clamping engagement between the member and clamp.

4. A support for a concrete floor screed, comprising a screed-supporting member extending upwardly from beneath the lower surface of the concrete floor to be cast, said member having a lower slotted end, a clamp engaging a portion of a floor joist beneath the lower surface of the floor, and means on an end of the clamp to slidably receive the slotted end of the first named member.

5. In combination with a metal floor joist having upper and lower chords, a support for a screed comprising a screed-supporting member having a longitudinal slot, a clamp having one end for engagement with the lower chord of the joist, and means on its opposite end for drawing the screed-supporting member against the side edges of both chords of the joist.

EDWIN C. GILSON.
